(57) **CLAIM**

The ornamental design for a vehicle light as shown and described.

DESCRIPTION

FIG. 1 is a top, front, right side perspective view of a vehicle light showing the claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof, and,

FIG. 7 is a bottom plan view thereof.

The dashed broken lines near the left and right sides of a triangular prism structure in FIG. 2 depict portions of the vehicle light that form no part of the claimed design.

The dashed broken lines in the drawing depict portions of the vehicle light that form no part of the claimed design.

1 Claim, 6 Drawing Sheets
